SWITCHING SYSTEM

William H. T. Holden, Woodside, N. Y., assignor
to Bell Telephone Laboratories, Incorporated,
New York, N. Y., a corporation of New York

Application February 8, 1941, Serial No. 377,990

8 Claims. (Cl. 179—18)

This invention relates to switching systems and particularly to those used in the establishment of telephone and other communication connections.

The objects of the present invention are to simplify these switching systems, to increase their speed of operation, to reduce the cost, and to obtain other improvements therein.

In automatic telephone systems where large groups of lines have access through switches, such as line-finders or line switches, to trunk groups it has been proposed heretofore to arrange these switches in primary and secondary formation with links for extending the lines to the trunks and also to arrange the switches and lines in coordinate rows or groups, such as horizontal and vertical groups, for the purpose of obtaining an orderly inter-connection of the lines with the trunks. In such a switching system it has usually been necessary to provide relay chains and rather involved control circuits for serving the lines having calls thereon, for preventing interference between simultaneous calls in the different groups, for insuring selection in preferred horizontal and vertical groups, for selecting idle groups of trunks, and for selecting idle 20 links having access to these trunk groups.

Accordingly, a feature of the invention is a system in which the relay selecting and testing mechanisms are replaced by electronic discharge devices which perform the selecting and testing functions with greater speed and with less complication in the control circuits. More specifically a plurality of discharge tubes are provided for the horizontal groups of lines and switches, and a second plurality of tubes are provided for the vertical groups. The presence of calls in these groups causes impulses to be applied to the corresponding tubes. These impulses have different phases characterizing the different horizontal groups, so that only one horizontal-group tube can discharge at a time, the discharged tube preventing other tubes from discharging by the simple expedient of altering the potential on their electrodes. Impulses of different phases are also applied to the vertical-group tubes, and the first tube to discharge in the series prevents any other tube from operating.

Another feature of the invention is a system in which the several groups of trunks to which a calling line, chosen to be served by the horizontal and vertical group selections above mentioned, has access are tested simultaneously with the links extending respectively between the chosen line and said trunk groups, said test being performed by means of a plurality of discharge 55

tubes. If the trunk group and the link having access to such group are both available, impulses are applied to the corresponding test tube. The impulses applied to each tube differ in phase from those applied to other tubes, so that only one tube can discharge in the event there are two or more trunk groups available at the time the test is made.

10 A further feature is a testing system in which the lines of a selected vertical group are tested by a series of discharge tubes to determine which line shall be served provided two or more are calling at the time. The selection is determined by applying impulses of different phases to the tubes, the tube that is first to discharge serving to render the others inoperative.

These and other features of the invention will be described more fully in the following specification.

In the drawings accompanying the specification:

Fig. 1 is a diagrammatic illustration of a frame of primary and secondary line switches for extending calling lines to idle trunks;

Figs. 2 to 8, inclusive, when arranged as illustrated in Fig. 9, show the detail circuits for controlling the operation of the primary and secondary line switches;

Fig. 2 shows a subscriber's line appearing in a 30 primary switch and also shows a secondary switch for extending the lines to idle trunks;

Fig. 3 shows the horizontal-group tubes and relays for selecting a horizontal group to be served;

35 Fig. 4 shows the vertical-group tubes and relays for selecting a vertical group to be served. This figure also shows the tubes for testing the line links between the primary and secondary line switches;

Figs. 5, 6 and 7 disclose the testing tubes for 40 selecting a group of trunks to serve the calling line and for selecting an idle trunk therein. Figs. 5 and 6 also show relays for closing the operating circuits of the switch magnets; and

Fig. 8 shows the testing tubes for choosing a 45 particular line to be served when a number of lines are calling simultaneously.

Referring to Fig. 1, the frame of line switches illustrated therein comprises ten horizontal 50 groups or levels of primary line switches of which three are shown, the No. 0 level 100, the No. 5 level 101, and the No. 9 level 102. Each of these primary line switches serves ten subscribers' lines, the lines appearing in the vertical rows of contacts of the switches. The line links appear in

the horizontal rows of contacts, which are multiplied from switch to switch in the corresponding horizontal group. The line switches are also arranged in vertical groups, and there may be as many as ten of these vertical groups. In the present disclosure, however, it will be assumed that there are seven vertical groups of primary switches, including the No. 0 vertical group 103, the No. 1 vertical group 104 and the No. 6 vertical group 105. Thus the primary switches 107, 108, 109 constitute the horizontal group 100; primary switches 110, 111, 112 constitute the horizontal group 101; primary switches 113, 114, 115 constitute the horizontal group 102; and other primary switches not shown constitute the remaining horizontal groups of switches. The lines appearing in each primary switch may be regarded as a subgroup of the corresponding horizontal group.

Ten secondary switches 116, 117, 118 are also provided on the frame, and the interconnecting line links serve to extend calls from each horizontal group of primary switches to each of the secondary switches. For example, the ten links 119 extend respectively from the horizontal group 100 to each of the ten secondary switches 116, 117, 118. Similarly, the ten links from each of the other nine horizontal groups extend respectively to the ten secondary switches. Each of the secondary switches has a group of ten outgoing trunks extending to succeeding selector switches and a group of ten incoming trunks for inward calls. For example, the outgoing trunk groups 120, 121, 122 extend to district selectors and serve calls originating on the subscribers' lines appearing in the primary line switches. Incoming calls to these subscribers' lines are completed over the incoming trunks 123, 124, 125.

The primary and secondary line switches disclosed herein may be of the well-known cross-bar type. The structure of these switches is disclosed in the patent to Reynolds, No. 2,021,329, of November 19, 1935. In the present disclosure the invention is illustrated in the circuits and devices for controlling the operation of these primary and secondary line switches to extend calling lines to idle trunks leading to succeeding switches. Although common register senders are used for receiving the designations from the calling lines and for controlling the selective operation of the selector switches, these senders have not been included in the present disclosure. They could, of course, be readily provided, and an understanding of the manner in which the senders are associated with the selected idle trunks may be had from the patent to Busch et al., No. 2,224,251, of December 10, 1940.

A general description will now be given of the circuits and equipment shown in detail in Figs. 2 to 8. The subscriber's line 200 and nine other lines not shown appear in the vertical rows of contacts in the primary switch 201. The line link 202 extending from the primary switch 201 appears in a horizontal row of contacts in the secondary switch 203. A second line link 204 extends from the primary switch 201 to another secondary switch not shown. Similarly the line link 205 extends from a primary switch, not shown, and appears in the horizontal row of contacts in the secondary switch 203. Two trunks are shown appearing in the vertical rows of contacts of the secondary switch 203. The trunk 206 serves a subscriber's line when calling and extends it, therefore, to a succeeding district selector switch. The trunk 207 serves to extend incoming calls

5 to the subscribers' lines and it leads, therefore, from an incoming selector switch. Trunk 208 is one of a group of ten similar trunks appearing in the secondary switch 203, and these ten trunks all extend to the same frame of district selectors.

The subscriber's line 200 is provided with an individual line tube 208 of the space discharge type in lieu of the usual line relay, and the same is true of all other lines in the system. The starting electrode 209 of the tube 208 is connected through a resistance 210 and contacts of the hold magnet 211 to the conductors of the subscriber's line. The cathode 212 is connected over a group start conductor 213 and through a resistance 308 and a contact of relay 400 to the negative pole of battery 401. When the subscriber makes a call, current flows from battery 228 over the loop of line 200 in a circuit including resistor 229. The drop across resistor 229 raises the electrode 209 to a positive potential, whereupon the control gap 209-212 ionizes. Conductor 213 is common to the tubes of the ten lines served by the primary switch 201; hence this conductor is multiplied to all ten of the cathode elements. In a similar manner the ten line tubes associated with each of the remaining six primary line switches in the horizontal row are connected to a common start conductor corresponding to the conductor 213. There are, therefore, seven of these start conductors for each of the ten horizontal rows or a total of seventy in all, and these start conductors all derive their current supply from battery 401.

35 The purpose of these start conductors is to ionize the start tubes of the group 305, of which there are ten, one for each horizontal group of line switches. Two are shown, tube 306 serving the No. 0 horizontal group and tube 307 serving the No. 9 horizontal group. The tube 306 is provided with seven start electrodes which serve the seven start circuits (including circuit 213) individual to the seven line switches of the No. 0 horizontal group. For instance, the circuit 213 extends through a condenser 301 and resistance 302 to one of these start electrodes, and in like manner the other six start circuits extend through corresponding condensers and resistors to the respective start electrodes of tube 306. And the same is true of the start circuits for the remaining nine horizontal groups. The remaining three start electrodes of each of tubes 305 are connected together and serve as a collector as will be explained more fully hereinafter.

55 The anodes of the line tubes are connected to an impulse generator 227 designed to produce a series of impulses often different phases. The impulse lead 214 for a particular phase (phase No. 0) is connected in multiple to the anodes of the tubes of all lines occupying the No. 0 position in all of the primary line switches. It may be assumed that line 200 occupies the No. 0 vertical row of contacts in the switch 201; therefore, the impulse lead 214 is connected to the anode 215 of line tube 208. The impulse lead 216 for phase No. 1 is similarly connected to the anodes of the tubes of all lines occupying the No. 1 vertical row of contacts in all of the vertical line switches. And the same is true of the impulse leads for the remaining eight phases. When, therefore, a line tube has its control gap ionized and the generator 227 delivers a positive impulse to the anode, such as anode 215 of tube 208, the tube discharges its main gap, and an impulse of positive polarity appears on the start conductor 213.

70 The impulse generator 227 which produces the

phase impulses for operating the line tubes, and the impulse generators to be described herein-after in connection with other parts of the control circuits disclosed herein, may be of any suitable type, such as those shown in the application of W. H. T. Holden, Serial No. 361,536, filed October 17, 1940; the patents to Holden No. 2,235,815, of June 9, 1942, and No. 2,252,766 of August 19, 1941.

In order that one horizontal group having calling lines therein may be served to the exclusion of other horizontal groups, a group of ten horizontal-group tubes 310 is provided. The ten tubes in this group are individual respectively to the ten horizontal groups of switches and are associated respectively with the ten start tubes 305. The No. 0 horizontal-group tube 311 has a starting electrode 312 which is connected over conductor 308 to the collector electrodes of the tube 306. The other start electrode 313 is connected to the impulse lead 314 which delivers negative impulses of phase No. 0 from the impulse generator 349. The cathode 315 is connected to the negative pole of battery, and the screen electrode 316 is connected through a common resistance 317 to the battery supply lead 318. Finally the anode of the tube 311 is connected through the winding of the associated horizontal-group relay 320 to the battery supply conductor 318. The electrodes of the remaining horizontal-group tubes are connected in a similar manner, the starting electrodes corresponding to electrodes 313-351 extending respectively to the impulse conductors for the successive phases. The screen electrodes 316-321 of the ten tubes are connected in multiple and through the common resistance 317 for the purpose of locking out all tubes as soon as one of them has operated. This lock-out function will be explained more fully hereinafter.

The ten horizontal-group relays 320-321 serve to extend the seventy start conductors through to the vertical group tubes 405. There are seven of these vertical-group tubes 406-407, one for each of the seven vertical groups of primary line switches. The start conductor 213 pertaining to the line switch 201 in the No. 0 vertical group and in the No. 0 horizontal group is extended by way of condenser 322 and conductor 323 through the contacts of horizontal-group relay 320 over conductor 324, condenser 408, resistor 409 to the starting electrode 410 of the vertical-group tube 406 pertaining to the No. 0 vertical group. Likewise the other six start conductors 325 pertaining to the other six primary switches in the horizontal group No. 0 and in the respective vertical groups are extended through contacts of relay 320 to the start electrodes of the other six tubes of the group 405. One of these, start conductor 326, pertaining to the No. 6 vertical group, is shown leading through the contacts of relay 320 thence over conductor 327, condenser 411, resistor 412 to the start electrode 413 of the No. 6 vertical-group tube 407. The other start electrodes 414-415 are connected in multiple and through a common resistor 416 to the negative pole of battery. The anodes 417-418 are connected respectively to the windings of associated vertical-group relays 419-420 to the battery supply conductors 421 and 318. The screen control electrodes 422-423 are connected in multiple through a common resistor 424 to the battery supply conductor 421. The purpose of the group of tubes 405 is to select one vertical group of lines for service to the exclusion of other vertical groups having simultaneous calls;

and the purpose of the associated relays 419-420 is to prepare operating circuits for the ten select magnets of the primary switch in the chosen horizontal and vertical groups.

Having chosen to serve the lines in a primary line switch of a particular horizontal group and of a particular vertical group by operating the corresponding one of the start tubes 305 and one of the horizontal-group tubes 310 and the associated relay and by operating the corresponding one of the vertical-group tubes 405 and the associated vertical-group relay, it is now necessary to make a joint test of each line link serving the chosen primary line switch and the group of trunks reached by the line link. This may be seen more clearly by referring to Fig. 1. If, for example, the line switch 113 is chosen to serve the group of ten lines appearing therein, then a test is made of the ten line links 126 and the ten groups of trunks reached respectively by these line links. A line link is not available for extending a call if it is busy or if all of the trunks to which it has access are busy. However, all links that are idle and have access to trunk groups containing idle trunks are available, and a choice is made of some one of these available paths in a manner to be described hereinafter.

The line links are tested by a group of ten tubes 430, each of the tubes 431-432 serving ten links. The ten links served by the tube 431 are those which have access through a particular secondary switch to the associated group of trunks. Therefore, the start electrodes of this tube represent respectively a link in each of the ten horizontal groups. Likewise the ten start electrodes of tube 432 represent respectively a link in each of the ten horizontal groups. And the same is true of the other eight tubes in the group 430. Corresponding electrodes in each of the ten tubes are connected in multiple relation. When the horizontal group is chosen, such as the horizontal group represented by the tube 311 and relay 320, a circuit is closed for applying potential to the start electrodes, one in each of the ten tubes 430, corresponding to the ten line links serving the chosen horizontal group. This circuit may be traced from the positive pole of battery 328 through the contacts of group relay 320, conductor 329 thence in parallel through resistors 425, 426 and 427, 428 and through the other sets of resistors (not shown) to the start electrodes of the ten tubes of the group 430. Thus a test circuit is prepared for the ten line links that serve the chosen group of lines. The positive battery potential on the start electrodes of these tubes indicates that the associated links are idle. However, any links that are busy at the time the test is made have ground potential on their test or sleeve conductors, and this ground potential is impressed upon the start electrodes of the tubes to identify them as busy links. For example, if the link 202 is busy, ground potential on the sleeve conductor 217 is extended by way of conductor 218 and resistor 426 to the associated start electrode of tube 431. Similarly, if the link 204, is busy, ground potential is extended over conductor 219 and through resistor 428 to the start electrode representing this link in the tube 432. The anodes of the link test tubes 430 are connected respectively to the ten phase impulse conductors over which positive impulses are supplied from the generator 433. The cathodes of these tubes are connected

in multiple over conductor 434 to the start electrodes 600 and 601 of the tubes 602 and 603.

The purpose of the tubes 602 and 603 is to make a matching test between the links and the corresponding trunk groups accessible to these links. Each of the ten trunk groups is provided with a test network for determining how many trunks are idle in the group. Three of these test networks 700, 701 and 702 are shown. The test network 700, for example, has ten parallel branches which include resistors 704, 705, 706, etc. When all trunks are idle, all of these branches are open, and each trunk taken in use causes the closure of the associated resistance branch. The several resistance branches are connected over a common conductor 707 through a common resistor 708 to the negative pole of battery 709, and the conductor 710 connected to the other terminals of the branch resistors, extends over conductor 711 through the contacts of relay 330 to the positive pole of battery 331. The conductor 707 is also connected to the midpoint of the secondary winding of the transformer 712 and thence in simplex over conductors 713 to the midpoint of the winding of transformer 714 over conductor 715 to the start electrode of tube 716, which is one of a group of ten tubes 720 individual respectively to the ten groups of trunks. The primary winding of transformer 712 is connected in multiple through the back contacts of relays individual to the ten trunks of the group, thence over conductors 723 to the ten phase impulse leads of generator 724. The ten trunk relays 725, 726, 727, etc., are normally deenergized when their respective trunks are idle and are in an operated condition when the trunks are busy. Each idle trunk, therefore, in the group of ten is indicated by the presence of impulses of the corresponding phase in the primary winding of the transformer 712. If all of the trunks are busy the resistance branches 704, 705, 706 are all open under the control of operated trunk relays, such as the relays 725, 726, 727, etc., and no circuit exists for the flow of current over conductors 710 and 711. Therefore, the full negative potential of battery 709 is impressed on the start electrode 728 of the tube 716 which represents the trunk group. Under this condition the tube 716 does not ionize since, as will be explained hereinafter, the cathode 729 is also at negative battery potential. If one trunk in the group is idle and the rest are busy, a single one of the branches is closed, and current flows from battery 331 over conductors 711 and 710 and through the closed branch to battery 709. The flow of current in the resistor 708 makes the electrode 728 more positive but not enough so to cause the ionization of the tube 716. If, however, two or more trunks are idle in the group, the amount of current flowing produces a drop in resistor 708 sufficient to cause the ionization of the tube 716.

In like manner the remaining trunk groups, each of which is represented by a test network 701, 702, are connected to the phase impulse leads of generator 724 and are tested for the presence of two or more idle trunks by the respective test networks and the individual tubes of the group 720.

The matching test for determining an idle line 70 link having access to a group of trunks containing an idle trunk is performed by the tubes 602 and 603 under the simultaneous control of the tubes 430 and 720, and the result of this test is registered by the operation of one of the group of 75

ten tubes 500. Each of the tubes of the group 500 represents a line link and the group of ten trunks to which the link has access. For example, the No. 0 tube 501 represents the No. 0 line link of any horizontal group and the group of ten trunks accessible to the No. 0 link, and the No. 9 tube 502 represents the No. 9 link and the associated group of trunks. To explain the matching test of links and trunk groups assume that each of the trunk groups represented by the test nets 700 and 701 has two or more idle trunks therein and that the trunk group represented by the test net 702 has only one idle trunk. On this assumption tube 716 has its control gap ionized by means of a circuit traceable from conductor 707, which is now positive, through the windings of transformers 712 and 714, resistor 730, control gap 728-729, conductor 731, conductor 732, winding of transformer 604, conductor 605, normal contact of relay 503 to the negative pole of battery 504. Also the tube 721 ionizes in a similar circuit. Tube 733, however, does not ionize since the current flow through a single resistance branch of the network 702 does not make the conductor 134 sufficiently positive. The anodes of the tubes 720 are connected respectively to impulse leads of generator 735 which delivers positive impulses of the ten phases No. 0 to No. 9. When, therefore, the impulse generator 735 produces the next impulse of phase No. 0 a positive potential is applied to the anode 736 of tube 716, and current flows from the anode to the cathode 729 over conductor 731 to the negative pole of battery 504 as previously traced. The current impulse of No. 0 phase flowing through the primary winding of transformer 604 induces an impulse of like phase but of negative polarity in the secondary winding, and this negative impulse is applied to the start electrodes 606 and 607 of the tubes 602 and 603. If at this instant the line link, such as the link 202, having access to the trunk group represented by the test net 700 is idle, the start anode 435 of tube 431 is at positive potential, and ionizing current is flowing from the electrode 435 to the cathode 436 and thence through inductor 437 to the negative pole of battery 438. At this same instant, namely, when the transformer 604 is delivering a negative impulse to the electrodes 606 and 607, a positive impulse of No. 0 phase is applied over impulse lead 439 to the anode 440. Since the tube 431 is ionized, current flows from the anode 440 to the cathode 436 thence through inductor 437 to the negative pole of battery 438. This current flow produces a positive impulse on conductor 434 which is applied to the start electrodes 600 and 601 of the tubes 602 and 603. Therefore, these tubes ionize their control gaps, and a circuit is now closed from impulse conductor 608 of phase No. 0 of generator 631, anode 609, cathode 610, resistance 611, to the negative pole of battery 612. This flow of current produces an impulse of positive potential which is transmitted through condenser 613 over conductor 614, normal contacts of relay 400 and conductor 441, resistor 505 to the start electrodes 506, 507, etc., of the ten tubes 500. Since the impulse generator 534 is delivering an impulse of No. 0 phase at this particular instant, this No. 0 phase impulse appears on impulse lead 508, and the other start electrode 509 of the tube 500 is raised to positive potential. The start gap 506-509 of the tube 501 now ionizes. The positive potential on conductors 318 and 421 is applied by way of conductor 510 and common resistor 511 to the con-

trol grids 512, 513, etc., of the tubes 500. Therefore, transfer takes place in the tube 501, and current flows from the positive pole battery over supply conductor 510, winding of the district group relay 514, anode 515, cathode 516 to the negative pole of battery. Thus the single tube 501 of the group 500 is selected and operated to identify an idle line link having access to a group of trunks containing at least two idle trunks. Current also flows through the common resistor 511 and the control grid 512 to the cathode 516. This flow of current in the common resistor produces a drop of voltage which lowers the positive potential of the control grids of the remaining tubes 500 to prevent another one from discharging even though other links and associated trunk groups are available for use.

When a moment later the impulse generator 735 reaches phase No. 1, an impulse is delivered over lead 737 to the anode of the ionized tube 721, and a current impulse flows through transformer 604. The transformer 604 delivers a negative impulse of phase No. 1 to the tubes 602 and 603, and one of these tubes may ionize its control gap provided at the same instant an impulse of phase No. 1 is flowing through one of the tubes of the group 430 indicating the idle condition of the line link having access to the trunk group represented by the network 701. The ionized tube 602 delivers an impulse to the starting electrodes of the tubes 500, but the corresponding tube in the group 500 cannot ionize at this time since it is locked out by the potential drop in the resistor 511 as a result of the operated condition of the tube 501. Two tubes 602 and 603 are used to secure a sufficient deionization interval between successive impulses, and for this reason odd-numbered impulse phases are connected to anodes of tube 603 and even-numbered to 602. For longer intervals between pulses, one 10 anode tube could be used, or for shorter intervals 3 or more might be needed.

The trunk group relays 514, 517, etc., serve to complete operating circuits for the switch magnets and also to extend the test circuits for the trunk groups through to the trunk test tubes 615. The operation of one of these relays, therefore, such as the relay 514, prepares the testing circuits for the group of trunks represented by the network 700. If the trunk represented by relay 725 is one of the two trunks of the group assumed to be idle, this relay is in a deenergized condition, and an impulse is delivered over the following circuit as soon as the impulse generator 724 reaches phase No. 0: impulse lead 738, conductor 739, resistor 740, normal contacts of relay 725 through the primary winding of transformer 712 to ground. This impulse is induced in the circuit 713 and is in turn induced in the secondary winding of the transformer 714, causing a current impulse to flow over a conductor 741 through the contacts of relay 514, conductor 518, normal contacts of relay 400, conductor 442, resistor 616 and thence in multiple to the start electrodes 617, 618, etc., of the ten tubes 615, each of which represents one of the trunks in the group of ten. These start electrodes 617, 618, etc., are raised to positive potential in the phase No. 0. At this same instant an impulse of negative polarity of phase No. 0 is applied from generator 632 over the impulse lead 619, resistor 620 to the other start electrode 621 of the tube 622. Tube 622 alone ionizes its control gap, and, since the control grid 635 is supplied with positive potential by way of conductors 510

and 623, transfer takes place to the main anode and current flows from the positive pole of battery over conductor 623 through the winding of relay 624, anode 625, cathode 626 to the negative pole of battery. Current also flows through the common resistor 627 in circuit with the control grid 635, and the voltage drop across the resistance lowers the potential of the control grids of the remaining tubes to prevent a second one from discharging. The flow of current in the anode circuit operates relay 624, which identifies the selected idle trunk in the group and prepares an operating circuit for the corresponding hold magnet of the secondary switch 203.

Having selected the horizontal and vertical groups to be served by operating the corresponding relays, such as relays 320 and 419, and having chosen an idle line link and an idle trunk in the group served by the line link, it now becomes necessary to choose the particular one of the ten subscribers' lines in the primary line switch that is to be served first, a number of which may be calling simultaneously. This line selection is made by the group of ten test tubes 800, each tube representing one of the ten lines in the chosen primary line switch. The start electrodes 801, 802, etc., of these ten tubes are connected individually to the phase impulse leads of generator 803. The other start electrodes 804, 805, etc., are connected in multiple through the common resistor 806 and condenser 807 to the impulse lead 808 which will be described presently. The cathodes 809, 810, etc., are connected in multiple through the common resistor 811 to the negative pole of battery 812. The anodes 813, 814, etc., are connected in multiple to the common conductor 815. The collector electrodes 816, 817, etc., are connected individually to the electrodes of a corresponding group of tubes 820, there being one of these tubes for each of the tubes in the group 800.

The impulse conductor 808, which is connected to the starting electrodes of the tubes 800, is an extension of the starting conductor 213 individual to the group of ten subscribers' lines in the chosen primary line switch. This extended start circuit may be traced from conductor 213 over condenser 322, conductor 323, contacts of horizontal-group relay 320, conductor 324, contacts of vertical-group relay 419 and thence to conductor 808. If a plurality of subscribers' lines are calling simultaneously in the group of ten lines, impulses of the corresponding phases are transmitted from the impulse conductors 214, 216, etc., through the individual line tubes to the start conductor 213 and thence to conductor 808 and to the starting electrodes of the tubes 800. If, following the completion of this extended start circuit, the first impulse to be transmitted is the impulse of No. 0 phase, the tube 818 alone ionizes its control gap since impulses are applied to its control electrodes simultaneously. The No. 0 phase impulse transmitted over the start conductor 808 to the control electrode 804 of tube 818 and to the corresponding control electrodes of the remaining nine tubes is of positive polarity; whereas the impulses delivered by the impulse generator 803 are of negative polarity. Therefore, a positive impulse is applied to electrode 804 and simultaneously a negative impulse to electrode 801. The ionization of the control gap of tube 818 transfers to the main anode as soon as the anode circuit is closed following the measurement of a time interval. This interval, which will be described presently, is introduced

to give the select magnets of the primary line switch time in which to operate.

At the time relays 320 and 419 operate a circuit is closed from the negative pole of battery through the winding of connecting relay 220, conductor 323, contacts of relay 320, conductor 324, contacts of relay 419, conductor 808, winding of relay 819 to the positive pole of battery. Relay 819 operates and closes the circuit from positive pole of battery thence over contacts of relay 322, which is being held operated as will be explained more fully hereinafter, contacts of release relay 333, conductors 318, 421 and 510, contacts of operated relay 514, conductor 519, contacts of relay 819, resistor 821, condenser 822 to ground. The condenser 822 charges and measures an interval of time, at the end of which sufficient potential is applied across the electrodes 823 and 824 of tube 825 to ionize the same. Thereupon a circuit is closed from positive battery potential on conductor 519 through the winding of relay 826 through the anode and cathode gap of the tube 825 to the negative pole of battery. Relay 826 operates and extends positive battery supply conductor 519 to conductor 815 and thence to the anodes of the tubes 800. As soon, therefore, as the control gap 801—804 of the tube 818 ionizes as above described, ionization transfers to the main anode 813 and current flows in a circuit traceable from the positive pole of battery thence over supply conductor 519, contacts of relay 826, conductor 815, anode 813, cathode 809 through the common resistor 811 to the negative pole of battery 812. The voltage drop across the resistor 811 lowers the potential of the cathodes of the remaining tubes of the group 800 to prevent another one from discharging subsequently if the corresponding lines are in a calling condition. After the tube 818 discharges, current flows from the anode 813 to the collector electrode 816 thence through resistor 827 and resistor 811 to the negative pole of battery 812. The flow of current in resistor 827 increases the positive potential of the electrode of tube 829. At this time the other control electrode 830 is connected by way of conductor 831, contacts of relay 220, winding of the primary hold magnet 211 to the negative pole of battery. It will be recalled that relay 220 is included in the circuit with relay 819 and is operated at this time. Tube 829 ionizes, and a circuit is now closed from the positive pole of battery 832, secondary winding of transformer 833, winding of relay 834, conductor 835, anode 836 of the ionized tube 829, cathode 830 and thence as traced through the winding of the hold magnet 211 to the negative pole of battery. The current flowing in this circuit, which is the sum of the current supplied by the direct current batteries and the alternating current generator 837, causes the operation of the primary switch hold magnet 211 to complete the connection from the calling line through to the selected idle trunk. Upon the extension of the connection to the selected trunk, ground potential is applied to the sleeve conductor of the trunk in any well-known manner to maintain the hold magnet 211 energized. When the alternating current source 837 enters the next opposing alternation the current flowing in the circuit of tube 829 is insufficient to maintain the main discharge from anode to cathode. The tube quenches and does not again discharge since the cathode 830 is now maintained at ground potential by way of the test conductor of the selected trunk. The relays 834 and 838

measure an interval of time and then bring about the release of the controlling circuits.

If at the time the test is made of the trunk groups no group has two or more idle trunks therein a further test is made to determine whether there is any group having a single idle trunk. This reserve test is made under the control of the tube 820 and the associated relay 503.

In order that a more complete explanation may be given of the operation of the system, the assumption will now be made that the subscriber's line 208 initiated a call and is connected through the primary and secondary line switches 201 and 203 to an idle trunk. It will also be assumed that line 208 is the No. 0 line in the primary switch at the intersection of the No. 0 horizontal and vertical groups on the line switch frame. When the subscriber of line 208 closes his line loop, the individual line tube 208 ionizes in the manner hereinbefore described, and an impulse of positive polarity of No. 0 phase superimposed on direct current of negative polarity is applied to the start conductor 213. The impulse circuit may be traced from the negative pole of battery 443, normal contacts of relay 400, conductor 444, impulse generator 227, thence over the No. 0 phase impulse lead 214, anode 215, cathode 212 to the start lead 213. The impulse produced by the generator 227, which is of positive polarity, appears on the start lead 213 and is applied through condenser 301 and resistor 302 to the start electrode 334 of the start tube 306. Since the cathode 335 is at negative potential, ionization occurs, and a discharge circuit is closed from the positive pole of battery 306, interrupter 337, when closed, left winding of relay 332, anode 338, cathode 335 to the negative pole of battery 306.

The interrupter 337 is designed to close the discharge circuit above traced at successive intervals and to maintain it closed for a period sufficient to permit the operation of the control circuits and the completion of the connection from the subscriber's line to the trunk. During this closed period of the interrupter, relay 332 is operated to close certain control leads, and the relay is made somewhat slow to release to provide a sufficient interval following the opening of the interrupter. If the interrupter 337 is open at the time the subscriber initiates the call, the phase impulses continue to occur in the start conductor 213 until the interrupter 337 closes, at which time the main discharge circuit of the tube 306 becomes effective as above described. The relay 332 operates in response to the flow of current in the discharge circuit of tube 306 and connects the positive pole of battery 306 through the normal contacts of release relay 333 to the battery supply conductors 318, 421, 510 and 623.

The potential set up on the collector electrodes 341 is applied over conductor 308 to the start electrode 312 of tube 311; and, when generator 348 applies the next impulse of No. 0 phase to lead 314, the tube 311 ionizes its control gap and the discharge transfers to the main anode, resulting in the operation of the associated horizontal-group relay 320. The operating circuit for relay 320 may be traced from conductor 318, which has positive potential thereon, winding of said relay, anode 319, cathode 315 to the negative pole of battery 342. As hereinbefore explained, the discharge of tube 311 causes current to flow in the circuit of the control grid 316 to disable the other tubes of the group 310.

When the horizontal-group relay 320 operates, the start lead 213 is extended over condenser

322 and conductor 323 to conductor 324, which further extends through the condenser 408 through resistor 449 to ground and through resistor 409 to the start electrode 410 of the vertical-group tube 406. The tube 406 ionizes its control gap, and immediately current flows from the positive pole of battery over conductor 421 through the winding of the vertical-group relay 419, anode 417, cathode 445 to the negative pole of battery 446. Relay 419 operates to identify the vertical group containing the calling primary line switch 201. Current also flows between the grid 422 and the cathode 445 in a circuit including the common resistor 424, and the voltage drop across this resistor makes the grids of the other tubes less positive, thereby preventing a second one from transferring its ionization to the main anode.

If two vertical groups are calling at the same time and the calling lines therein occupy the same position in the line switches, impulses of the same phase are delivered over the start wires to the electrodes 410-413 of the corresponding tubes 406-407. Due to the varying characteristics of the tubes, one of them will increase its ionizing current to the transfer value in advance of the others. This flow of transfer current, although small in value, sets up a voltage across the common resistor 416 which lowers the potential on the start electrodes of the other tubes, thus impeding the ionization of a second tube until the first one has transferred its ionization to the main anode.

The horizontal-group relay 320 in operating closes a circuit from ground over conductor 343, contacts of relay 320, conductor 344 through the winding of the select magnet 221 of the secondary switch 203. The select magnet 221, which is individual to the horizontal row of contacts in which appears the single line link 202 extending from the calling primary switch 201, prepares the contacts in this horizontal row for connecting the link to any one of the group of ten outgoing trunks, such as the outgoing trunk 206. Relay 320 also closes an operating circuit for relay 330 which may be traced from battery, resistor 345, winding of relay 330, contacts of relay 320, conductor 346 to ground at the normal contacts of relay 400. Relay 330 applies battery potential over the leads 628 to the trunk group testing circuits shown in Fig. 7 preparatory to the performance of the group test to determine which groups have idle trunks therein. Moreover, the horizontal-group relay 320 applies positive battery potential over conductor 329 to one of the start electrodes in each of the ten line link test tubes 430.

Assume that the group of ten trunks including the trunk 206 to which the line link 202 has access has two or more idle trunks therein and that this group of ten trunks is represented by the testing network 700. Further, it may be assumed that trunk 206 is one of the idle trunks and is represented by the individual relay 725 and that relay 726 represents another of the idle trunks in the group. Relays 725 and 726 are, therefore, in a released condition, and the circuit branches 704 and 705 are closed. As hereinbefore explained, the current flowing from battery 331 over conductor 711 through branches 704 and 705 in parallel and resistance 708 to the negative pole of battery 709 produces a potential drop across resistor 708 which is applied to the electrode 728 of the tube 716 and is sufficient to cause the ionization of said tube. As soon there-

after as generator 735 delivers a positive impulse of No. 0 phase on generator lead 742, current flows in the main discharge gap of the tube 716 producing an impulse in the transformer 604 which causes the application of a negative potential to the electrodes 608 and 607 of the matching test tubes 602 and 603. If at this same instant the line link 202 is idle, no ground potential is applied over conductor 218 to the starting electrode 435 of the tube 431, and the starting gap of this tube is in an ionized condition when the positive impulse of No. 0 phase is applied over the impulse lead 439 to the anode 440 of the tube. Hence, discharge current flows in the main gap of tube 431, and an impulse is applied over conductor 434 to the electrodes 600 and 601 of the tubes 602 and 603. These tubes ionize their starting gaps; and, since at this same instant a positive impulse of No. 0 phase appears on generator lead 608, current flows over anode 609, cathode 610, resistor 611 and the negative pole of battery 612. This flow of current impresses an impulse on conductor 614 which is applied over the circuit previously traced to the start electrodes 506, 507, etc., of the ten trunk group tubes 500. At the same instant that this impulse appears on the electrodes 506 and 507, an impulse of No. 0 phase is applied over generator lead 508 to the electrode 509 of the tube 501. This tube discharges to the exclusion of the remaining tubes and identifies the selection of the trunk group containing the idle trunk 206. The operation of the tube 501 results in the flow of current from conductor 510 through the winding of relay 514, anode 515, cathode 516 to the negative pole of battery 521. Current also flows between control grid 512 and cathode 516 in a circuit including common resistor 511, and the drop across this resistor lowers the potentials on the grids of the remaining tubes to prevent a second one from operating subsequently. Relay 514 in operating closes a circuit from ground over conductor 522, contacts of said relay, conductor 523, resistance 45 345 to battery. This circuit shunts the relay 330, and the latter releases to remove battery potential from the conductors 628 so that the trunk groups may be available for test at other line switch frames. Before relay 330 releases, however, to remove battery potential from conductor 710, the relay 514 closes a substitute circuit from the positive pole of battery 524, conductor 525, contacts of relay 514, conductor 526 to conductor 710. Thus battery potential is maintained on the test circuits of the selected trunk group until the connection to an idle trunk therein is completed. The operated trunk group relay 514 also completes a circuit for energizing the primary switch select magnet 222. This circuit may be traced from battery through the winding of said magnet, conductor 223, contacts of the vertical-group relay 419, conductor 447, contacts of relay 514 to ground. The magnet 222 operates and prepares the contacts in the horizontal row 55 in which the selected line link 202 appears.

Next, an idle one of the trunks in the chosen group is selected for use. If all trunks in the group except those represented by relays 725 and 726 are busy, one of these two trunks will 70 be selected depending upon the phase of the impulse generator 724 at the time relay 514 is operated. If, following the operation of relay 514 an impulse appears on the No. 0 phase lead 738 prior to the appearance of an impulse on the No. 1 phase lead 743, the trunk represented by

relay 725, namely, trunk 206, is selected. The positive impulse of phase No. 0 on lead 738 is applied over conductor 739, resistor 740, normal contacts of relay 725 to the primary winding of transformer 712. By induction in transformers 712 and 714 this impulse appears as a positive impulse on conductor 741, over which it is applied through the contacts of relay 514, conductor 518, normal contacts of relay 400, conductor 442, resistor 816 to the start electrodes 617, 618, etc., of the ten trunk test tubes 615. At this same instant a negative impulse of No. 0 phase is being applied over lead 619 to the starting electrode 621 of the tube 622. This tube ionizes, and current flows from the positive pole of battery over conductor 623, winding of relay 624, anode 625, cathode 626 to the negative pole of battery 629. Current flowing through the common resistor 627 in the circuit of the control grid 635 alters the potential of the control grids of all other tubes to prevent a second one from operating. Relay 624 in operating closes an operating circuit for the secondary switch hold magnet 224, which is individual to the selected idle trunk 206. This circuit may be traced from battery through the normal contacts of relay 400, conductor 448, operating winding of select magnet 204, conductor 225, contacts of relay 624, conductor 630, contacts of relay 514 to ground.

The lines in the primary line switch 201 are now tested to determine which ones are calling and to select one of these calling lines for connection to the selected trunk 206. Since line 200 is in a calling condition, the start conductor 213 is extended through condenser 322, conductor 323, contacts of relay 320, conductor 324, contacts of relay 419, conductor 808 through condenser 807 through resistor 848 to ground and through resistor 806 to the start electrodes 804, 805, etc., of the ten line test tubes 800. Since the multi-contact relay 220 is connected in multiple to the conductor 323, it operates in series with relay 819 which is connected to the conductor 808. The relay 220 is individual to the primary line switch 201 and serves to extend the operating circuits of the hold magnets through to the cathodes of the ten corresponding discharge tubes of the group 820. Relay 819 in operating extends the conductor 519 through resistor 821 to the condenser 822. Condenser 822 charges at a rate depending upon the resistance 821 and measures an interval sufficient to permit the operation of the primary switch select magnets. At the end of this interval the tube 825 ionizes and discharge current flows to operate the relay 826. Relay 826 extends the positive pole of battery over conductor 519 through the contacts of relay 826 and conductor 815 to the anodes of the tubes 800.

Upon the next appearance of a positive impulse of phase No. 0 over the start conductor 213 and thence over the path previously traced on the start electrode 804 a negative impulse of the same phase is applied over impulse lead 839 to the start electrode 801, and the tube 818 ionizes. Current now flows in the anode-cathode circuit, the remaining tubes are disabled by the voltage drop in the common resistor 811, and the voltage drop across the resistor 827, as a result of current flow in the circuit of the collector electrode 816, applies a positive potential to the electrode 828 of the tube 829. Tube 829, therefore, ionizes its control gap since negative potential is applied over conductor 831 to the

electrode 830. Current now flows in the circuit traceable from the positive pole of battery 832, secondary winding of transformer 833, relay 834, conductor 835, anode 836, cathode 830, conductor 831, contact of relay 220, winding of the primary switch hold magnet 211 to the negative pole of battery. The current flowing in this circuit is increased and diminished by the value of the alternating current component produced by the generator 837. This current is sufficient to operate the hold magnet 211, which completes the establishment of the connection from the calling line 200 over the link 202 through the secondary switch 203 to the selected idle trunk 206. In the well-known manner the trunk 206 returns ground potential to hold the magnets 224 and 211, and this ground potential is further extended over the conductor 831 to the cathode 830 of the tube 829. When the component of the generator 837 next opposes the battery 832, the voltage drop between the anode and cathode of the tube 829 is insufficient to maintain ionization since ground potential has now been applied to the cathode. Therefore, the tube 829 quenches and does not reoperate as long as ground potential is maintained on the cathode thereof.

At the time relay 834 operates it closes an obvious circuit for the operation of slow-release relay 838. When relay 834 releases at the time 30 the tube 829 quenches, a circuit is closed from ground over the back contact of relay 834, front contact of relay 838, conductor 848, conductor 841, winding of release relay 833 to battery. Relay 833 operates and opens the supply circuit 35 from battery 840. Thus all of the operated relays and tubes in the line switch control circuit are restored to their normal condition. After an interval relay 838 releases and opens the circuit of release relay 833.

At the time relay 826 operates a circuit is closed from the positive pole of battery over conductor 519, contacts of relay 826, resistor 842 to the condenser 843. The condenser 843 is charged in series with the resistor 842 and measures an interval of time sufficient to permit the controlling circuits to complete their functions. If release of the controlling circuits does not proceed in the regular manner, the condenser 843 reaches its charged condition, and the tube 844 ionizes. 40 Current now flows from the positive pole of battery over conductor 519, relay 845 through the tube 844 to the negative pole of battery 846. Relay 845, which is slow to release, closes a circuit from ground through the contacts of operated relay 834, conductor 847, operated contacts of relay 826, operated contacts of relay 845 to conductor 841. This operates the release relay 833 and brings about the release of the controlling equipment as above described.

60 The timing condensers 822 and 843 are discharged by circuits closed through the back contacts of relays 819, 826, 838 and 834.

If the initial test of the trunk groups indicates that no group has two or more idle trunks therein, a reserve test is made to determine whether any group has a single idle trunk. The reserve test is made at the end of a measured interval which is long enough to enable the test and selection of any group that is found having two or more trunks. This interval is measured by a circuit traceable from battery supply conductor 318, conductors 352 and 354, resistor 355, contacts of relay 330, conductor 347, resistor 521 to condenser 528. At the end of the interval the condenser reaches its charged condition, and full

positive potential is applied through resistor 529 to the electrode 530 of tube 520. Tube 520 ionizes since the other control electrode 531 is connected through the winding of relay 503 to the negative pole of battery 504. Current now flows in a circuit from the positive pole of battery over conductor 623, anode of the tube 520, cathode 531, winding of relay 503 to the negative pole of battery 504. Relay 503 operates in this circuit and increases the negative potential applied over conductor 605 to the electrodes of the tubes of the group 720. This increased potential is applied from the negative pole of battery 532 in series with battery 504 through the contact of relay 503, resistor 533, contact of relay 503 to conductor 605. Hence the voltage drop across the electrodes of any one of the tubes 720 is sufficient to ionize the tube if one of these electrodes is connected to a testing network 100 having only one of its branches closed, indicating that only one of the trunks in the group is available.

The line switch frames disclosed herein also serve to complete incoming calls to the called subscribers' lines. For a general understanding of the operation of primary and secondary cross-bar switches for the completion of both outgoing and incoming calls, reference may be had to the patent to W. W. Carpenter, No. 2,089,921, granted August 10, 1937.

One of the terminating switch controlling markers 450 is illustrated diagrammatically in the drawings. Whenever the marker 450 seizes the line switch frame for the purpose of completing a terminating call to one of the subscribers' lines, relay 400 is operated over a circuit extending from the marker over conductor 451 through the normal contacts of relay 332 (no outgoing call being extended at this time) conductor 348 to the winding of relay 400 to battery. Relay 400 operates and removes battery potential from conductor 213 and similar conductors to prevent the operation of any one of the line tubes in case one of the subscribers initiates a call. Relay 400 also opens other control leads that are used when outgoing calls are being extended. In a similar manner the extension of an outgoing call prevents the terminating marker 450 from seizing the line switch frame. This is accomplished by opening the energizing circuit of relay 400 at the contacts of relay 332.

The phase impulse generator leads disclosed in various parts of the drawings may be connected to separate generators, all of which are in synchronism, or to the same impulse generator. These phase impulses are produced during each cycle of an alternating current source of any suitable frequency. As has been explained, some of these impulses are of positive polarity and others are of negative polarity. Generally speaking the discharge tubes disclosed in the drawings are designed to ionize their control gaps when a voltage is applied thereto which is equal to the sum of the positive and negative potential impulses, whereas a single impulse is insufficient. Large amplitude pulses are required in the anode circuits, as in tube 208, in which case the direct current component of anode voltage is insufficient to maintain a discharge, while the sum of the direct voltage and the peak impulse voltage in the anode, less the drop in the tube while conducting will result in an impulse of normal amplitude across an output impedance. I have found that suitable values are 75 volts and 75

50 volts positive, and 50 volts negative are suitable peak impulse amplitudes.

What is claimed is:

1. In combination, a plurality of switches arranged in groups, groups of lines appearing respectively in said groups of switches, a plurality of space-discharge devices, one for each of said groups of lines, a source for producing potentials of different phases, said phases characterizing respectively the different groups of lines, means including said source responsive to the lines of each group for applying to the corresponding discharge device impulses of the phase characterizing said group to cause the discharge of said device, means effective when any one of said devices discharges to prevent the discharge of any one of the other discharge devices, and means responsive to the discharged device for controlling the operation of the switches of the associated group.
2. In combination, a plurality of switches arranged in groups, groups of lines appearing respectively in said groups of switches, a plurality of discharge tubes, one for each group of lines, means responsive to the lines of each group for applying to the corresponding tube impulses of potential to cause the discharge thereof, the impulses applied to the different tubes being of different phases to cause a single one of said tubes to discharge at a time, means effective when any one of said tubes discharges to prevent the discharge of any other tube in response to the potential impulses applied thereto, and means responsive to the discharged tube for controlling the operation of the switches of the associated group.
3. In combination, a plurality of switches arranged in groups, groups of lines appearing respectively in said groups of switches, a plurality of space-discharge tubes, one for each group of lines, means for applying a control potential to all of said tubes, means responsive to any line in each of said groups for applying to the corresponding tube operating potential impulses to cause the discharge of said tube, the impulses applied to the different tubes being of different phases to insure that only one tube discharges at any time, means effective when any one of the tubes discharges for altering the control potential on the remainder of said tubes to render them unresponsive to said operating potential impulses, and means controlled by the discharged tube for causing the operation of the associated switches.
4. In combination, a plurality of lines arranged electrically in coordinate horizontal and vertical groups, switches for serving said lines, a series of discharge tubes individual respectively to the horizontal groups, a second series of discharge tubes individual respectively to the vertical groups, a source of potential of different phases, each phase characterizing a different one of said horizontal groups of lines, means responsive to a calling line in any horizontal group for causing the application to the corresponding tube of potential impulses from said source of the phase characterizing said horizontal group to effect the discharge of said tube, means effective when any one of said horizontal-group tubes discharges for rendering the remaining horizontal-group tubes unresponsive to potential impulses, means responsive to the discharge of a tube individual to a horizontal group of lines for applying potential impulses to the tubes individual to said vertical groups, means responsive to the discharge of one

of said vertical-group tubes for rendering the remaining vertical-group tubes unresponsive to said potential impulses, and means controlled by the discharged horizontal and vertical tubes for causing said switches to serve the coordinate group of lines represented by said discharged tubes.

5. In combination, automatic switches, a group of lines appearing in said switches, a plurality of groups of trunks, a plurality of link circuits accessible to said switches for extending said lines to said trunk groups, said link circuits having access respectively to said trunk groups, means for performing a matching test between each link circuit and the trunk group to which it has access, said means comprising a plurality of space-discharge tubes, one for each link and its associated trunk group, means for producing potential impulses of different phases characterizing the idle links, means for producing potential impulses of different phases characterizing the idle trunk groups, and means for applying to said tubes potential impulses of the phases representing idle links that match with idle trunk groups to cause the discharge of one of said tubes, means responsive to the discharge of one of said tubes for disabling the remaining tubes, and means controlled by the discharged tube for causing the operation of said switches to extend a connection over the chosen idle link and trunk group.

6. In combination, a plurality of switches, a plurality of lines appearing in said switches, a number of trunk groups, a number of links accessible to said switches for extending said lines to said trunk groups, said links having access individually to the respective trunk groups, a testing mechanism comprising a series of discharge tubes for making a matching test of the links and the associated trunk groups, said tubes serving individually the respective links and their associated trunk groups, means for producing potential impulses of different phases characterizing the respective links, means for transmitting to said testing mechanism impulses of the phases representing idle links, means for producing potential impulses of different phases characterizing the respective trunk groups, means for transmitting to said testing mechanism potential impulses representing trunk groups having an idle trunk therein, means responsive to the potential impulses of like phase transmitted

5 to said testing mechanism for causing the application of potentials of like phase to said discharge tubes to cause the discharge of one of said tubes representing an idle link having access to an idle trunk, and means responsive to the discharged tube for causing the operation of said switches.

7. In combination, a plurality of switches, a plurality of groups of lines appearing respectively in said groups of switches, each group of lines divided into subgroups which appear respectively in the individual switches of the corresponding group, means for selecting a group of lines to be served to the exclusion of other line groups, means for selecting a subgroup of lines in the chosen group to be served to the exclusion of the other subgroups in said chosen group, means for producing potential impulses of different phases representing the different lines of the chosen subgroup, a series of discharge tubes each representing one of the lines of said subgroup, means for applying said potential impulses to said tubes to cause the discharge of one of said tubes, and means controlled by the discharged tube for operating the associated switch to serve a particular line represented by said tube.

8. In combination, a plurality of switches, a plurality of groups of lines appearing respectively in said groups of switches, each group of lines divided into subgroups which appear respectively in the individual switches of the corresponding group, means for selecting a group of lines to be served to the exclusion of other line groups, means for selecting a subgroup of lines in the chosen group to be served to the exclusion of the other subgroups in said chosen group, means for producing potential impulses of different phases representing the different lines of the chosen subgroup, a series of discharge tubes each representing one of the lines of said subgroup, means for applying to said tubes potential impulses of the phases characterizing calling lines in the chosen subgroup for causing the discharge of one of said tubes to the exclusion of the other tubes, means controlled by the discharged tube for disabling the remaining tubes, and means controlled by the discharged tube for causing the operation of the associated switch to extend the chosen line.
